ASH HANDLING SYSTEM

Ernest C. Webb, Bay Village, Ohio, assignor to
Iron Fireman Manufacturing Company, Portland, Oreg.

Application September 11, 1945, Serial No. 615,544

5 Claims. (Cl. 110—165)

1

This invention relates generally to stokers and particularly to an ash elevator for use in conjunction therewith.

The main object of this invention is to provide a means for accumulating and storing ashes that will utilize most advantageously the space that may be available near the boiler or furnace. In other words, I have endeavored to obtain the maximum practical storage capacity when occupying the minimum number of square feet of floor space.

The second object is to provide a simple and efficient form of distributing mechanism and storage buckets which will provide the maximum amount of ash storage without requiring an undue amount of physical effort in the disposition of the ashes after being collected.

The third object is to provide an improved form of storage can which will not be difficult to empty.

The fourth object of this invention is to so construct the ash handling system that the various joints may easily be rendered dust tight.

I accomplish these and other objects in a manner set forth in the following specification as illustrated in the accompanying drawings, in which

Fig. 1 is a front view of the ash handling system, showing its relation to a furnace with portions broken away to disclose certain related parts.

Fig. 2 is a plan of the ash removal section with the cover removed.

Fig. 3 is a fragmentary vertical section taken along the line 3—3 in Fig. 2, showing the cans in a lowered position.

Fig. 4 is a fragmentary section taken along the line 4—4 in Fig. 2, showing the cans in a raised position.

Fig. 5 is a plan of the entire battery of ash cans.

Fig. 6 is a perspective view of one ash can.

Fig. 7 is a vertical section through the ash elevator and the upper portion of the ash distributing section, showing the relation of the parts.

Fig. 8 is a fragmentary section taken along the line 8—8 in Fig. 7.

Similar numerals refer to similar parts throughout the several views.

Referring in detail to the drawing, there is shown a furnace 10 having the usual coal feeding worm 11 and air duct 12 of a stoker (not shown), by means of which air and coal are delivered to the retort 13.

Ashes 14 are ejected by the horizontal ash discharging worm 15, through the horizontal ash

collection tube 16. The mechanism thus far described is in common use.

In Figs. 7 and 8 are shown the means for elevating the ashes to a higher level. In Fig. 7 it will be seen that the ash tube 16 extends into the flanged end 17 of the elevator base 18, whose closed end 19 is provided with a bearing 20, in which journals the end 21 of the ash worm shaft 22. Between the flights of the ash worm 15 and the end of the shaft 22 is a reverse flight worm 23, which is joined to the ash worm 15 by the longitudinal paddle 24, which is substantially radial to the axis of the shaft 22.

Mounted over the base 18 is an elevator body 25 on one side of which is formed an inclined duct 26, whose inlet 27 is directly above the paddle 24 and communicates with the interior of the base 18 at that point, while its upper end 28 is provided with a discharge lip 29, over which ashes 14 may be discharged into the elevator which I am about to describe. Mounted on the body 25 and preferably insulated therefrom by means of a rubber gasket 30, is a square casing 31. The upper end of the casing 31 is connected to a head 32 by means of a rubber bushing 33. Mounted in the head 32 is a horizontal ash discharge tube 34, whose end 35 projects well beyond the supporting boss 36, which is secured to the head 32 by means of a flange 37 and bolts (not shown). The tube 34 is held against movement with relation to the end 36 by means of a set screw 38. The end 39 of the tube 34 is closed except for an opening for the shaft 40 of the ash discharge worm 41. The shaft 40 has secured thereon a V-belt pulley 42, by means of a set screw 43. Surrounding the tube 34 is a loose V-belt pulley 44, which is supported by the semi-friction bearing 45, which in turn is held in relation to the tube 34 by means of the set screw 46. The shaft 40 journals in the bearing 47, which is mounted in the covered plate 48, which in turn is secured to the head 32 by means of the bolts 49.

On the shaft 22 are secured the V-belt pulleys 50 and 51 around which extend the flat belt 52, whose V-sections 53 and 54 engage the pulleys 50 and 51 respectively, while the intermediate portion of the belt 52 bridges the gap between the pulleys 50 and 51. It will be noted that since the pulley 42 is secured to the shaft 40 while the pulley 44 is loose on the tube 34, the driving action of the belt 52 is exerted only on the pulley 42. Secured to the interior of the flat portion of the belt 52 are the buckets 55, into which ashes are discharged over the lip 29 by the worm sections 15 and 23 and paddle 24.

The mechanism thus far described collects ashes from the furnace 10 and elevates them and discharges them through the tube 34. Any equivalent mechanism for accomplishing this purpose may be employed without departing from the spirit of this invention.

Turning now to my invention as more clearly set forth in Figs. 2 to 6, it will be seen that the ash distribution and storage unit consists of an outer casing 56, over the top of which is placed a removable cover 57 and beneath which is formed a floor 58. Disposed under the floor 58 are a battery of ash cans 59, which are shown in plan in Fig. 5. Each ash can 59 is elongated, as shown in Fig. 6, and tapered about one fourth inch per foot. In normal practice the cans are about four and one half feet tall and six inches square at the top, and about four and one half inches square at the bottom. All four sides are tapered, but a lesser number may be tapered without seriously detracting from the utility of the device. Around the upper end of each ash can 59 is secured an angle bar rim 60, beneath which is secured a handle 61. Below the handle 61 is secured the elongated hinged handle 62, which is made fast to the cross straps 63.

The floor 58 is provided with a plurality of round holes 64, one over each can 59. Resting on the floor 58 is a distributing plate 65 provided with holes 66, all of which can register with the holes 64 at the same time when the distributor plate 65 is moved in one direction in order to permit ashes to flow therethrough into the cans 59, whereas all of the holes 64 may be closed when the plate 65 is moved into the position shown in Fig. 2. The plate 65 is provided with two slots 67, through which extend the bolts 68 which, like the bolts 69 disposed beyond the outer boundaries of the plate 65, extend through the short horizontal shafts 70 and the long horizontal shaft 71. The bolts 68 and 69 pass freely through the upright tubes 72, which are secured to the floor plate 58. The lower ends of the bolts 68 and 69 pass through the horizontal bars 73.

Partition walls 74 extend between the floor and the back of the casing 56, while the transverse wall 75 extends between the partitions 74. The walls 74 are provided with slots 76 to permit the free vertical movement of the shafts 70 and 71.

Mounted on the shafts 70 and 71 are the rollers 77 and 78. Beneath the rollers 77 and 78 are disposed the plates 79, having the inclined cam surfaces 80 formed thereon, upon which the rollers 77 and 78 can rest, as shown in Fig. 3, allowing the cans 59 to move to a lowered position, that is, one in which they can be withdrawn from the casing 56 by opening the door 81. It is desirable to provide a rubber gasket 82 on the under side of the floor 58, against which the rim 60 of the ash cans 59 can press when the cans 59 are in a raised position, as shown in Fig. 4. The plates 79 are secured to the distributor plate 65. One set of plates 79 are separated, as shown in Fig. 3, to provide clearance for the discharge tube 34, while the other plate 79 is provided with a slot 83 as shown in Fig. 4, to provide clearance for the worm shaft 40, which journals in the bearing 84, which in turn is secured on the floor 58 by means of the bolts 85. Also secured on the floor 58 is a standard 86, through which extends the discharge tube 34. The end 35 of the discharge tube 34 extends through the wall 74.

Journaling in the bearing 84 and the standard 86 is a shaft 87, on which are secured the pinions

88 and 89 respectively. The pinions 88 and 89 mesh with the racks 90 and 91, which are secured across the top side of the members 79 by means of the bolts 92. Motion is imparted to the shaft 87 by means of the crank 93.

The operation of this portion of the device is as follows: Assuming that the buckets 55 are carrying ashes 14 upwardly on the inside of the belt 52, it follows that when they reach the uppermost 10 turn of the belt that they will be dumped and fall through an opening 94 in the tube 34, and are then carried by the discharge worm 34 onto the plate 65. It follows that the ashes will be deposited upon the plate 65 and will fall through 15 the nearest holes 64 and 66 if they are in register. When any particular can 59 is filled, the ashes are pushed onto the next nearest unfilled can. If the attendant does not empty the cans, the only damage which can occur is to raise the cover 57 and 20 permit the ashes to spill upon the floor outside of the cabinet. If it is desired to remove the cans 59, it is only necessary to rotate the crank 93 which causes the plate 65 to slide to the position shown in Fig. 2, that is, so that the holes 64 and 25 66 are out of register, the last portion of the movement causing the cans 59 to be lowered.

While I have thus illustrated and described my invention, it is not my desire to be limited to the precise form shown herein, and I intend to cover 30 such forms and modifications of the invention as fall fairly within the appended claims.

I claim:

1. An ash handling system consisting of an elevated floor having apertures formed therein, an apertured plate slidably mounted on said floor, its apertures adapted to register with those in said floor when said plate is moved to a pre-determined position and to move said apertures out of register in another position, means for elevating 35 ashes and distributing same upon said plate, a plurality of elongated vertical ash cans slidably mounted under the apertures in said floor and means for sealing said cans against the under side of said floor when in a filling position.
2. An ash handling system consisting of an elevated floor plate having a plurality of elongated, elevated ash cans slidably disposed thereunder, said floor plate having apertures therein communicating with said cans, a slidable plate 40 mounted over said floor plate having apertures formed thereon, means for moving said plate to bring the apertures of said floor plate and said slidable plate in and out of register, an ash elevating system for raising ashes from a furnace and 45 depositing them upon said slidable plate and means for moving said ashes horizontally across the surface of said slidable plate toward the vari-out perforations therein.
3. An ash handling system consisting of an elevated floor having a plurality of apertures formed therein, an apertured plate slidably mounted upon said floor, the apertures registering in one relative position of the floor and plate, said plate forming a closure for the floor apertures in a second position of said plate, a plurality of ash cans suspended under said apertures and horizontally slidably thereunder, means for elevating 50 said cans into contact with the under side of said floor in a manner to form a seal around the edge of each can, an ash elevating and distributing means for delivering ashes upon said plate and to distribute same across the surface thereof.
4. An ash handling system consisting of an 55 enclosed cabinet having a floor disposed below

the top of said cabinet, a plurality of vertically movable horizontal bars disposed under said floor in spaced relationship to each other, a plurality of elongated ash cans having outwardly flanged rims adapted to be disposed between said bars and supported thereby, said floor having openings therein communicating with said ash cans, an apertured plate slidably mounted on said floor plate constituting a valve for all of said openings, means for manually moving said apertured plate and a cam actuated by said plate for raising and lowering said bars, whereby a movement of said plate to close said openings will be followed by a movement of said bars to lower said cans in order that said ash cans may be slidably withdrawn from between said bars.

5. An ash handling system having an upright rectangular ash cabinet with means for elevating ashes to the top of the cabinet in combination with a plurality of elongated vertical ash cans disposed within said cabinet, means for slidably supporting said cans in rows, said cabinet having an opening in the side thereof, through whch said cans can be removed by sliding same horizontally, means for raising and lowering said ash can sup- 25

5 porting means, a floor disposed over said ash cans having openings therein communicating with said cans, said floor having sealing means disposed along the under side adapted to engage said cans when raised, and an apertured plate constituting a sliding valve disposed upon said floor, together with a cam attached to said plate, adapted to lower said ash cans when said plate is moved to close the openings in said floor
